UNITED STATES PATENT OFFICE.

BENJAMIN ADRIANCE AND AMOS CALLESON, OF BROOKLYN, NEW YORK; SAID CALLESON ASSIGNOR TO SAID ADRIANCE.

APPARATUS FOR FORMING HOLLOW SHEET-METAL BODIES.

940,914.

Specification of Letters Patent. Patented Nov. 23, 1909.

Application filed June 25, 1908. Serial No. 440,313.

To all whom it may concern:

Be it known that we, BENJAMIN ADRIANCE and AMOS CALLESON, citizens of the United States, residing in Brooklyn, county of Kings, State of New York, have invented certain new and useful Improvements in Apparatus for Forming Hollow Sheet-Metal Bodies; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

The purpose of this invention is to provide a practical means for imparting to sheet metal vessels having plain or straight sides a bulging form without the use of female dies or supporting means of any kind coöperating with the male die in giving the required shape to the side wall of the article.

In carrying out our invention, we provide a continuous series of radially movable expanding members and an actuating member therefor disposed centrally and movable axially thereof, said expanding members and the actuating member having a wedge-like engagement the one with the other so that upon the downward thrust of the latter the expanding members will be moved radially outwardly to expand the vessel being operated upon; in addition, means is provided whereby, upon the return movement of the actuating member, the expanding members will retract to their original position, *i. e.*, to an extent sufficient to permit them to clear the now relatively contracted mouth of the vessel and, whereby, thereupon, the actuating member will effect the elevation, bodily, of the series of expanding members so as to withdraw the whole from the vessel ready for its next operation on another vessel.

The invention will be found fully illustrated in the accompanying drawing, wherein,

Figure 1 is a plan view of the device, herein termed a "chuck", forming the subject hereof; Fig. 2 is a view showing the actuating member partly in side elevation and partly in vertical section and the series of expanding members in vertical section, the plane of section being substantially coincident with the axis of the chuck; Fig. 3 is a horizontal sectional view on the line $x-x$ of Fig. 2; Fig. 4 is an isometric view of one of the parts of the series of expanding members; and, Figs. 5 and 6 show the vessel before and after being subjected to the action of the chuck.

It will be understood that the chuck herein described is carried by the vertically reciprocating plunger of a suitable press, which plunger operates toward and from the bed plate of such a machine.

Referring to Figs. 1, 2 and 3, *a* is the part hereinbefore referred to as the "actuating member". This consists of the truncated cone *b* having the upwardly projecting stem *c*, whereby to attach it into the plunger of the press, and a downwardly projecting stem *d*; the lower end of the cone has the lesser diameter, but that diameter is somewhat greater than that of the stem *d*, so that a shoulder *e* is formed. Onto the stem *d* is fitted another truncated cone *f* whose lower end is substantially flush with the end of stem *d* when said cone abuts, in the proper arrangement of the parts, against the shoulder *e*, in which position it may be held by the countersunk head *g* of a screw *h*. While in the foregoing and in the drawings the two cones are represented as non-integral parts and the cone *f* is described as having a substantial support against the shoulder *e*, so that to all effects and purposes the two cones are as rigidly disposed relatively to each other as though they were integral, it will be understood that we are not limited to forming said cones as separate bodies of metal.

The upper end of cone *f* has a greater diameter than the lower end of cone *b*, thus forming the shoulder *i*.

j designates one of the parts forming the series of expanding members. Each of these is shaped substantially as shown in Fig. 4, to wit, in plan, as a sector-shaped body having the upper portion *k* of its inside face inclined at a pitch corresponding to that of the cone *b* and the lower portion of said face inclined to a pitch corresponding to that of the cone *f*, as at *l*. The surfaces *k* and *l* are thus substantially parallel with each other, and they are joined by a surface *m*, substantially parallel with the end faces of the part *j*, and forming an abutment to take the impact of the shoulder *i* of cone *f*.

The several parts *l* are arranged in circular disposition, as best seen in Fig. 1, relatively to member *a*. They are furthermore formed with a continuous external groove *n*, 5 which receives an endless spiral spring *o* tending to contract the series and thus cause them to move bodily downward on the actuating member *a*, the surfaces *k* and *l* of said members bearing on the faces of the 10 cones.

The acting portion of the expanding members is approximate to the lower half, more or less, thereof; accordingly each part *j* has its outer surface in the lower part thereof 15 convex, as at *p*.

In the operation of the chuck, which is assumed to be operatively attached to the plunger of the press, the vessel to be shaped is placed over the chuck which, at that time, 20 is elevated from the bed plate and has assumed its contracted form since, being clear of the bed plate beneath it, the spring *o* is free to draw the members *j* together to an extent limited by the contact of their abutments *m* with the shoulder *i*. When the plunger of the press descends, the vessel is brought against its bed plate, directly taking the thrust of the members *j* whose downward movement is thus checked. It will 25 be understood that the vessel substantially fits the chuck in its contracted condition. Although the members *j* are prevented from further downward movement by the opposition of the bed plate, the actuating member 30 *a* is still free for further downward movement, and as this now follows, the cones *b* and *f* cause the series of members *j* to be expanded, they acting to expand or bulge the vessel. On the return or upward movement 35 of the plunger of the press, the spring *o* operates to contract the members *j* as above described, this action continuing until the shoulder *i* takes against abutments *m*, whereupon the vessel may be removed from the 40 chuck as soon as the chuck has assumed the proper elevation relatively to the bed-plate.

It will be observed that the bottom of the chuck is slightly concave, which effect is produced by imparting a slightly inclined 45 disposition to the lower face of each member

j. As a result of this, the vessel is allowed to assume a concave form in its base or bottom wall.

It will be observed that the means acting to contract the series of expanding members 55 is disposed between the lowermost and uppermost points of contact between said members and the actuating member, that is, in a plane cutting the zone of wedge-engagement between the members; thus any tendency 60 toward the producing of an oscillating or "rocking" movement on the part of the expanding members under the action of the actuating member, as might be possible were said means located outside of (instead of 65 between) these points, is prevented and each expanding member moves inwardly under a condition of perfect face-to-face contact with the actuating member.

Having thus fully described our invention, 70 what we claim as new and desire to secure by Letters Patent is:

The combination, in a bulging chuck, of a continuous series of radially movable expanding members, said series of members 75 having downwardly tapering upper and lower inside face-portions and a shoulder between said upper and lower face-portions, an actuating member surrounded by said expanding members and comprising a downwardly tapering truncated cone forming a shoulder at its lower end, a relatively reduced stem projecting from the lower end of said cone and another downwardly tapering truncated cone arranged on said stem 80 and abutting against the second-named shoulder, said last-named cone having its upper end larger than the lower end of the first-named cone and adapted to engage the first-named shoulder, and a contracting 85 means surrounding said series of expanding members, substantially as described.

In testimony, that we claim the foregoing, we have hereunto set our hands this 22nd day of June, 1908.

BENJAMIN ADRIANCE.
AMOS CALLESON.
